(57) CLAIM

The ornamental design for a collapsible bottle, as shown and described.

DESCRIPTION

FIG. 1 is a top perspective view of a collapsible bottle, shown extended in a first configuration;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan thereof;

FIG. 8 is a top perspective view of the collapsible bottle, shown collapsed in a second configuration;

FIG. 9 is a front view thereof;

FIG. 10 is a rear view thereof;

FIG. 11 is a left view thereof;

FIG. 12 is a right side view thereof;

FIG. 13 is a front view of the collapsible bottle, shown in the first configuration with the cover removed for clarity of disclosure;

FIG. 14 is a top view thereof; and,

FIG. 15 is a front view of the collapsible bottle, shown in the second configuration with the cover removed for clarity of disclosure.

The broken lines in the figures show portions of the collapsible bottle which form no part of the claimed design.

1 Claim, 15 Drawing Sheets
